GRENADE GUN

Stewart D. Long, Laurel, Md.

Application February 19, 1942, Serial No. 431,578

2 Claims. (Cl. 42—1)

This invention relates to a grenade and a gun for the shooting thereof, and has for the primary object the provision for more accurately propelling a grenade to a selected target than would be possible by manual throwing thereof and eliminates the necessity of a person having to take a substantial standing position as would be required in throwing the grenade, consequently allowing the person to assume a position which would be less hazardous or less apt to be hit by enemy projectiles.

Another object of this invention is the provision of a grenade approximately the size of a hand type grenade so that a large number of such grenades may be handled and carried by a person and the gun is of such construction that the person may conveniently operate said gun from the shoulder without disadvantages of any kind and has provision for permitting the firing mechanism of the grenade to be released at any time desired after the placing thereof in the gun, so that after the release of the firing mechanism has taken place, the person may aim the gun at a selected target and fire the propelling charge of the grenade through the operation of the gun as would be usual with any type of gun used from the shoulder. Further, the gun is of a construction to permit the grenade to be easily placed therein and to eject the shell of the grenade after a firing operation and also permit the gun to be taken apart for cleaning, convenient handling, carrying and storing.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawings, in which

Figure 1 is a side elevation, partly in section, illustrating a gun and the grenade therein, and showing in dotted lines the barrel positioned for loading and unloading.

Figure 2 is a fragmentary side elevation illustrating the barrel of the gun and a portion of the breech block as well as the slide for giving entrance to the barrel of the gun through the operation of the firing mechanism of the grenade.

Figure 3 is a transverse sectional view taken on the line 3—3 of Figure 2.

Figure 4 is a vertical sectional view illustrating the grenade and showing in detail the shell and propelling charge for the grenade.

Figure 5 is a perspective view of the shell prior to its application to the grenade.

Referring in detail to the drawings, the numeral 5 indicates as an entirety a gun especially constructed for the firing of a grenade 6, similar in construction to the hand-thrown type of grenade commonly used in warfare with the addition of a shell 7 containing a detonator 8 and a propelling charge 9. The casing of the grenade is slightly modified from the casing now employed by the hand-thrown grenade by being provided with a smooth portion 10 for contact with the riflings 11 of the barrel 12 of the gun. The grenade casing has a series of grooves to define portions 13 acting as shrapnel when the grenade bursts under the explosion of the charge contained within the casing thereof. Also, the grenade 6 includes the conventional timed firing mechanism (not shown) and equipped with the safety pin 14 which must be removed in order to set the timed firing mechanism in operation.

The shell 7 is equipped with a wadding 15 separating the propelling charge from the casing of the grenade, and also located in the shell is a packing 16 arranged between the walls of the shell, wadding 15 and the casing of the grenade.

The grenade is releasably held in the shell 7 by bending the edges of the shell into a groove provided in the casing of the grenade.

It will be seen that this construction of grenade is readily adaptable for use in a gun of the character shown in the drawings and indicated in entirety by the character 5.

The gun 5 has a shoulder stock 17, and a breech block 18 as well as a conventional type of trigger-operated firing mechanism 19. The barrel 12 of the gun is mounted on the breech block in a conventional manner so that the barrel may be swung relative to the breech block for loading and unloading thereof. The barrel adjacent to the breech is provided with a hand opening 19 normally closed by a slide 20 equipped with a finger piece 21 for the operation of said slide and which is shaped to form a rear gun sight. The front gun sight is indicated by the character 22 located on the barrel adjacent the muzzle thereof. The purpose of the hand opening 19 is to permit the operator of the gun to easily reach the releasing pin 14 of the grenade, after the placing of the latter within the barrel.

The slide 20 includes flanges 23 slidably fitted within grooves provided in the barrel so that the operator of the gun may readily move the slide to either cover or uncover the hand opening 19.

Any type of ejector, operated by the movement

of the barrel 20 relative to the breech block, may be employed for ejecting the shell 1 after the grenade has been fired by the gun. The barrel of the gun is of a length shorter than the average type of gun fired from the shoulder. However, the length of the barrel is sufficient to assure the flight of the grenade in a straight course to a given target. The shortness of the barrel has a distinct advantage of permitting the gun to be easily handled and aimed at a target and also to render the carrying of the gun comparatively easy.

A grenade of the character described and fired from the gun especially constructed therefor will permit a person to be more accurate and destructive against an enemy than could possibly be obtained through the use of a hand-thrown type of grenade. Also a person is free to assume a less hazardous position than when using the hand-thrown type of grenade. Further, the gun being especially constructed and designed for shooting a grenade eliminates the use of gun attachments which are now frequently adapted to army rifles for the shooting of grenades and is believed will be more practical and accurate in the hitting of a target with the grenade.

While I have shown and described the preferred embodiment of my invention, it will be understood

that minor changes in construction, combination and arrangement of parts may be made without departing from the spirit and scope of the invention as claimed.

Having thus described my invention, what I claim is:

1. In a gun, a rifled barrel, a breech block movably connected to the barrel to permit movement of the barrel relative thereto for the loading of the barrel with a grenade having a safety release for the control of the timed firing mechanism thereof, a shoulder stock on the breech block, said barrel having a hand opening in a wall thereof for the manual removal of the safety release, and means for opening and closing the hand opening.
- 10 2. In a gun, a rifled barrel, a breech block pivotally connected to the barrel to permit movement of the barrel relative thereto for the loading of the barrel with a grenade having a safety release for the control of the timed firing mechanism thereof, a shoulder stock on the block, said barrel having a hand opening in a wall thereof adjacent the breech block to permit manual removal of the safety release, and a closure plate slidably on the barrel for opening and closing the hand opening and including an offset to provide a finger piece.

STEWART D. LONG.
